FIG. 5.

UNITED STATES PATENT OFFICE.

JOHN SIDNEY HEATH, OF THOMAS STREET, OXFORD STREET, MIDDLESEX,
COUNTY, ENGLAND.

IMPROVEMENT IN BREECH-LOADING FIRE-ARMS.

Specification forming part of Letters Patent No. 138,887, dated May 13, 1873; application filed
September 6, 1872.

To all whom it may concern:

Be it known that I, JOHN SIDNEY HEATH, of Thomas street, Oxford street, in the county of Middlesex, England, have invented a new and useful Improvement in Breech-Loading Fire-Arms, of which the following is a specification:

My improvements are exclusively applicable to breech-loading fire-arms, more especially those in which fixed ammunition is employed. The object of the invention is, principally, to prevent the premature or accidental discharge of fire-arms; and it consists in the provision of sliding bolts for locking the firing-pins, the same being operated by a thumb-lever arranged to project through the gun-stock.

In the drawing, Figure 1 is a partly-sectional elevation of a double-barreled gun provided with my improvements. Fig. 2 is a transverse section of Fig. 1 on the line *x x*. Fig. 3 represents the lock mechanism in side view. Fig. 4 is an under-side view of a snap piece or tongue formed on the breech of the gun-barrel, and Fig. 5 is a plan view of the trigger-plate.

A is the gun-stock; B, the barrel; C, the breech-bed; and D, the tail-piece. No. 1 represents a thumb piece or lever projecting up through a slot in the tail-piece, and acting on lever No. 2, which, in turn, acts on lever No. 3. Both the last-named levers are pivoted in lugs formed on the under side of the tail-piece. Lever No. 3 is bent downward at its front end to form the pendent arm E, which acts on the short arms of the pivoted angle-levers *f f*, Fig. 2. These levers are acted on by springs *g g*, and their office is to draw the bolts *f' f'*, which are interposed between the levers *g' g'* and the rear wall of the stationary breech-block, thereby preventing the action of the firing-pins, except when the thumb-piece No. 1 is pressed down. *h h* are springs secured to the breech-block by screws, the upper ends of which fit in notches formed in the under side of the shorter arms of the aforesaid angle-levers, thus tending to keep the bolts *f'* in the position indicated in Fig. 2. The lock

proper, shown in Fig. 3, is mainly such as has been heretofore used in guns or small-arms, M *s* being the mainspring; R *r*, the sear; S *g*, the sear-spring; N, the stationary bridge-piece or bridle. M is a tumbler, pivoted at W to the piece N, and connected with the spring M *s* by the link S. The tumbler M is curved and extended at its lower end in such a manner as to act on the lower end of the lever *g'* when the gun is cocked, and thus cause the same to draw back the firing-pin.

From the foregoing it will be perceived that it is impossible to discharge the gun so long as the levers *g'* are locked by the bolts *f'*, and these last can be drawn back or toward each other, so as to offer no obstacle to the movement of the levers *g'* and the firing-pins, by no other means than by pressing on the thumb-piece No. 1. This pressure can be applied by the right hand grasping the small or reduced middle portion of the breech-stock when the gun is being aimed or sighted.

The trigger-guard plate L has four short slots, L *x*, through which pass the two parts or tongues *e e* of the triggers, the front parts or tongues being pivoted to an inner projection, *j*, of the plate L, and the rear tongues serving to act on the sears when the gun is fired. The construction avoids forming long continuous slots in the guard-plates, as commonly practiced, the object being to exclude dust more or less. A lug, K, is formed on the under side of the breech end of the barrel, and a bolt, K *x*, works transversely through a slot in said lug and through the breech-bed.

A projection or lug, *a*, inclined or beveled on its outer side, comes in contact with the spring of the bolt K *x*, which is thus held back until the barrel is closed, when the spring is released and throws the bolt forward, thus locking the barrel. The bolt is drawn out so as to release the barrel by means of a projecting handle-piece.

My invention is equally applicable to single and double barreled guns.

I claim—

1. The combination of a firing-pin, a lever,

g^x , a locking-bolt, f^x , and suitable mechanism for operating the same, as specified.

2. The combination of the lever or thumb-piece No. 1, levers Nos. 2 and 3, and spring x' with the firing-pin, step-bolts, and the levers g^x , as shown and described.

3. The combination, with the levers g^x and firing-pins f^x , of the tumblers M, a sear, and

co-operating springs S g and M s , as specified.

J. S. HEATH. [L. S.]
